UNITED STATES PATENT OFFICE.

MICHAEL J. TRACY AND JULIUS H. KINTZELE, OF ST. LOUIS, MISSOURI.

DESIGN FOR A LOCK CASE.

Application filed November 3, 1928. Serial No. 28,759. Term of patent 14 years.

To all whom it may concern:

Be it known that we, MICHAEL J. TRACY and JULIUS H. KINTZELE, citizens of the United States, and residents of the city of St. Louis and State of Missouri, have invented a new, original, and ornamental Design for Lock Case, of which the following is a specification, reference being had to the accompanying drawing, forming part thereof.

In the drawings, Fig. 1 is a top plan view showing our new design for lock case.

Fig. 2 is a front elevation.

Fig. 3 is a lower end elevation.

Fig. 4 is a side elevation.

Fig. 5 is a side elevation showing the opposite side from that shown in Fig. 4.

We claim:

The ornamental design for a lock case, as shown.
